UNITED STATES PATENT OFFICE.

EDWARD C. DANDY AND WILLIAM TUGWELL, OF BALTIMORE, MARYLAND.

BRAIDING MACHINE AND METHOD.

Application filed May 20, 1925. Serial No. 31,489.

To all whom it may concern:

Be it known that EDWARD C. DANDY and WILLIAM TUGWELL, citizens of the United States of America, both residents of the city of Baltimore, State of Maryland, have invented certain new and useful Improvements in Braiding Machines and Methods, of which the following is a specification.

In the operation of the standard type of braiding machine as illustrated and described in United States Patent No. 553,623, the point of each heart cam is one of the most exposed portions of the walls of the carrier track or groove and, subject to maximum wear due to friction and shock in the passing of the followers and particularly in the change of direction of the followers in entering and leaving the loop, passing from and to the main circular track.

To deflect the followers from the main circular track and cause them to enter the loop, the outer wall of this main circular track is provided with a deflecting portion in the form of an obtuse angled apex opposite the tangent point of each loop and directly opposite the point of the heart cam and spaced therefrom by a distance equal to or slightly greater than the width of the track. This is another point of maximum wear due to shock and friction of the followers as they are deflected in entering and leaving the loop, and there are two other points which may be referred to as points of maximum wear, at the termination of the inside wall of the main circular track at each side of the intersection of the main circular track with each loop track, the four points of maximum wear forming the points of an elongated diamond or lozenge, which is, however, slightly distorted from true diamond shape. This distortion is partly due to the deflection of the main circular path on each side of the entrance to each loop, which deflection brings this portion of the circular path into alignment with the connecting portion of the loop and incidentally forms the obtuse apex referred to opposite the point of the heart cam on the outside wall of the circular path.

As already pointed out, the four points referred to are points of maximum wear due to the friction of the followers and to the shock incident to deflecting them from the main circular path into the loop, and in passing from the loop into the main circu-

lar path. Excessive wear at these points soon takes place, resulting in increased hammering and friction, which wear and friction continue to increase until the parts lock or the machine becomes practically inoperative.

The centre plate and corresponding heavy parts are ordinarily made of cast iron which is a comparatively soft and easily abraded material which wears rapidly at the exposed points.

In regular practice when the machines are properly maintained, the centre plates or tables are replaced at considerable expense as soon as the points of deflection referred to become seriously worn, wear at other points in the path being comparatively slow and otherwise of little importance as the greatest necessity for smooth and accurate guidance of the followers occurs at the points of deflection.

One of the main features of the invention resides in the improvement of the centre plate whereby wear of the path at the points of deflection is practically eliminated without greatly increased expense of construction and whereby other advantages particularly, increased precision in positioning the operative parts relatively to each other, and increased efficiency as to both time and accuracy in assembling are attained.

In the preferred form, as illustrated, the hard metal by which the points are armed is in the form of pins, and the pins are seated by boring suitable holes in the centre plate parallel to the axis of the plate, thus removing the metal from the points and making holes for the pins below the points, and pushing or driving the pins into their final position in the holes.

In addition to the guiding and actuation of the bobbin carriers by the parts already described, they are further guided and aligned by a top plate which is placed above and secured to and rotated with the centre plate and is provided with a track or path parallel to and exactly overlying the path already described and engaged by an aligning follower. The path in the top plate differs mainly from the path in the centre plate in that it does not include the deflecting apexes forming part of the outside wall in the lower track opposite each intersection of the loop tracks with the main circular track, the function of deflecting the followers from

the main circular track into the loop and from the loop into the main track being served mainly by the guiding or bottom followers co-operating with the centre plate 5 track. In the centre plate the portions encircled by the loops are integral but the similarly encircled portions of the top plate known as heart cams, are rigidly supported on the centre plate directly over the corresponding portions of the centre plate, and this support may also serve as a bearing for the corresponding star wheel.

A further important function or object of the invention is to locate and position the upper heart cams relatively to the corresponding portions of the bottom plate, and particularly to position the upper heart cams and the star-wheel bearing relatively to the main points of deflection of the bottom plate 10 track already described and to hold the star-wheel bearing and the upper heart cams in their relation to these points which themselves may be referred to as stationary. This has been an expensive operation requiring fine adjustment and an important difficulty 15 has been that incident to the displacement of the upper heart cam and the star-wheel bearing due to the hammering of the followers resulting from wear at the points of deflection.

An accomplishment of the present invention in addition to increased convenience and accuracy in placing these parts and points in proper relation to each other, is the securing 20 of the parts in position, so that they cannot become displaced and in the greatly increased speed with which the positioning and assembling of the parts in their proper relation are performed.

40. The heart cams, which from the nature of things are necessarily separate from the top plate, are mounted on upright supports which are also the bearing members which carry the star-wheels which swing the carriers and followers about the loops, and it is 45 very important that the heart cams be accurately placed relatively to the points of deflection and to the outside walls of the loops in the top plate, and the corresponding portions of the loop in the centre plate, and it is 50 also important that the heart cams be rigidly secured against displacement, as the shock of the carriers and followers incident to deflection is effective to a considerable extent in tending to displace the heart cams, and this 55 is particularly true when the points of deflection on the centre plate become worn and any dislocation of the heart cams tends to produce harmful binding and knocking, rendering the machine inefficient and in time inoperative due to breakage and dislocation of parts.

In the form of the invention shown, the upright or star-wheel bearing is secured to 60 the centre plate, and each heart cam is se-

cured to the corresponding star-wheel bearing by means of a central bolt which passes through a cylindrical stud which latter forms the said bearing. In the preferred form of the invention this cylindrical stud 70 which bears on the top surface of the centre plate and the bottom surface of the corresponding heart cam, is connected to the centre plate and to the heart cam, not only by the central bolt but by pins in the cam 75 entering the top of the stud and pins connecting the plate to the bottom of the stud. Each pin is seated in a hole drilled for the purpose. An important feature of the invention resides in the fact that the holes for 80 the pins which are used to arm the points of deflection and the holes for the pins which secure the heart cam to the stud and the stud to the centre plate, may be located in relation to each other and to the parts in 85 which they are bored by means of jigs which give absolute accuracy of spacing and arrangement. In this way the relation of the points and paths and heart cams is accurately determined without difficulty, and the 90 parts are permanently placed, so that dislocation is practically impossible, and the arrangement is uniform in all instances and exactly as desired. Not only is the convenience of assembling the machine with the 95 necessary degree of accuracy greatly increased, but the life of the machine is indefinitely extended by reduction of wear at the vital parts, i. e., the points of deflection, and the permanent and accurate positioning 100 of the heart cams.

We have illustrated portions of a braider constructed and combined in accordance with the preferred form of our invention.

In the drawing—

Figure 1 is a plan of a centre plate showing the driving pinion and a fragmentary portion of an annulus in their operative arrangement.

Figure 2 is a plan on an enlarged scale 110 showing a fragment of centre plate surrounding and including one of the loop portions and also showing a follower in section.

Figure 3 is a section on the line 3, 3 of 115 Fig. 4.

Figure 4 is a top plan view showing principally the top plate.

Referring to the drawings by numerals, each of which is used to indicate the same 120 or similar parts in the different figures, the machine illustrated is of the familiar type already referred to, used for making braided rope as window cord and the like, the invention having particular relation to the 125 arm of the points of deflection and to the manner of securing the portions of the top plate known as the heart cams.

The portion of the machine illustrated 130 comprises a centre plate 1 having peripheral

gear teeth 2, pinion 3 driving the centre plate, stationary annulus 4 having teeth 5, star-wheels 6 mounted on bearing studs 7, which bearing studs are secured to the centre plate 1 by means of bolts 8 and nuts 9, top plate 10 secured to the centre plate in any suitable manner, separate heart cams 11 secured to the centre plate by the bolts 8, each heart cam 11 being placed on the corresponding stud 7 and fastened by a corresponding bolt 8. The illustration also includes spindle or bobbin carriers 19, each carrier having a shank or pin 12 which extends downward from the carrier through the path or slot 14 in the top plate and into the path 13 in the centre plate, portions of the pin or member 12 which contact with the respective slots being elongated laterally and flattened on the inner face at 15 and curved convexly to the outer face 16 or otherwise shaped to form followers, the upper follower members which co-operate with the top plate, being indicated by reference character 17, and the lower follower members which co-operate with the centre plate being indicated by reference character 18.

More specifically the path 13 in the centre plate includes a main circular track 20 which path is concentric with the plate and is in the form of a groove encircling the plate near the outside and spaced inward slightly from the bases of the teeth. The track or path 13 also includes loops 21 shown in this instance as four in number, which loops 21 approach the circular outline and may be described as spaced equally apart along the circular path and tangent thereto, the radius of each loop from the centre to the tangent point being slightly elongated so that the portions 22 enclosed within each loop are formed each with a point 23 disposed outwardly in a radial direction, i. e., toward the main circular track 20, and in the centre plate the outer wall of the track is provided with corresponding points or projections 24 opposite each of the points 23 and spaced therefrom a distance substantially equal to or slightly greater than the width of the path, the projection or point 24 serving to deflect the followers into the loop, which is continuous with the circular track in both directions from the tangent point.

In accordance with the well-known operation of this type of machine, the carriers 19 are engaged in turn and carried about each respective loop by star-wheels 6, see Figure 3, the arms 26 of the wheels engaging the carriers as to the waist portion 27 thereof between the followers, each carrier after it has encircled a loop being delivered to one of the recesses 28 of the annulus and held thereby until taken up by the next star-wheel, it being understood that the annulus is stationary and the centre plate constantly rotating, and that the star-wheels are driven

by engagement of the teeth 29 thereof with the teeth 30 of the annulus.

As already pointed out, the maximum wear due to the maximum of shock and friction occurs at what may be termed the four points of deflection 23, 24, 33 and 34 at the intersection or tangent point of each loop 21 with the main circular track, and as wear at this point causes knocking and detracts from the efficiency with which the cams are deflected from the main circular track to the loop track and returned from the loop track to the main circular track, and the wear when once begun, rapidly increases, the tendency to wear is considered one of the important defects of the machine as now in use.

To overcome the difficulty thus pointed out and thereby increase the life of the machine and improve its operation, and for other purposes pointed out in the statement of invention and to be further discussed, the applicants have armed the points of deflection 23, 24 and 33, 34 with hard metal, which presents many times the resistance to abrasion and shock presented by the cast iron material of the centre plate as previously constructed, and this arming of the points of deflection is accomplished in accordance with a method which is a feature of the invention and which makes it possible to place these points in the exact relation to the loop path and circular path intended with exact uniformity in every instance and with the least expenditure of time and material, and, further, in such a way as to reduce the cost of assembling the heart cams in the desired relation to the top plate, and both the cams and top plate in the desired relation to the centre plate and point of deflection, the method being such that the arming of these points and the placing of the heart cams becomes in the main a jig operation.

The method consists in drilling the top plate at the points 23, 24, 33, 34 at the apexes of the intersection of the walls of the follower path, 20, 21 with the loop, thus removing the metal forming each point and making a hole beneath and driving or otherwise setting in the holes thus formed round hard metal pins 35, 36, 37, 38, which when thus placed form the follower contacting portions of these points of intersection, entirely relieving the cast iron walls of the groove of the excessive wear due to contact with the follower at these points. These main points of contact being formed of wear-resisting material, the cast iron surfaces immediately adjacent these points are so protected that the wear of such surfaces becomes almost immaterial, and the life of the structure is correspondingly increased.

Another difficulty with such machines, as already outlined in the statement of invention, relates to the mounting of the heart

4
cams 11, Fig. 4, and the tendency of these cams to become displaced due to the knocking of the followers, which as aforesaid is greatly increased when the parts become worn. In accordance with the present practice of building and assembling the machines, the task of setting these cams in the first instance is one which consumes a great amount of time.

- 10 The present invention provides means for locating the heart cams 11 relatively to the points of deflection 23, 24, 33, 34, making this a jig operation which can be performed with the greatest accuracy in a comparatively short period of time and therefore with greatly reduced expense, and when so located the cams are firmly secured, so that there is no possibility of displacement due to loosening of the parts, and, further the location of the cams is absolutely uniform and accurate in all instances.

15 The method consists in drilling in each heart cam and spaced away from the central aperture 40 which receives the bolt 8, pin holes 41, which extend through the cam and down into the bearing member 7, respectively, whereby the cams may be pinned to the bearing member 7 with absolute uniformity in every instance. The bearing member 7 20 and centre plate 1 are also drilled with holes 42 on each side of the hole 43 in the latter, which receives the bolt 8 and in these holes are inserted pins 44. It will be apparent that by means of a suitable jig the pins 35, 36, 37, 38 or the holes to receive them and the holes 42 to receive the pins 44, may be placed in relation to each other with extreme accuracy, and that in turn the holes 41 may be likewise accurately located relatively to 25 holes 42. The holes 41 in the heart cams which co-operate with the holes 41' in the bearing member, may be by similar means located with extreme accuracy relatively to the surfaces of the heart cam, and when the 30 holes are all thus bored, the parts may be assembled with ease in such a way as to make the relation of the heart cam to the points of deflection 23, 24, 33, 34 and to the remainder of the track, absolutely definite and uniform in every instance, and when the 35 points of deflection are so armed and the heart cams are pinned in position as described, and further secured by the bolts 8, not only is the wear at the point of intersection of the loop track and the main circular track greatly reduced, the life of the machine correspondingly increased and the tendency to knock eliminated, but the tendency to dislocate the heart cams interfering 40 with the operation of the machine, is likewise overcome.

45 We have thus described specifically and in detail a single embodiment of our invention and the method of practicing the same in order that the nature and operation of the

device and method of assembling may be clearly understood; however, the specific terms herein are used descriptively rather than in a limiting sense, the scope of the invention being defined in the claims. 70

What we claim and desire to secure by Letters Patent is:

1. In a braider having a centre plate with a main track and a loop track intersecting the main track, so that the operative surfaces of the track meet in points at the intersection, means for arming said points comprising hard metal pins seated in the centre plate, the surfaces of the pins forming part of the operative surface at the points of intersection and resisting the friction and shock of the followers in passing from the circular track to the loop track and vice versa and preventing wear at this point. 75

2. In a braiding machine, a centre-plate 80 having a circular groove which serves as a follower track and loop tracks in the form of grooves joining the main circular track, carriers having followers co-operating with said grooves, a top plate having a corresponding track in the form of a slot, carriers having followers to co-operate with the top plate slot, separate cam members forming the inner walls of the loop track in the top plate, star-wheels and an annular gear for actuating the star-wheels, means for rotating the centre plate and top plate, means for supporting and securing the cams comprising an upright stud for each cam forming a bearing for the star-wheel and a support for the cam, and means for securing the cams and the studs to the centre plate comprising a plurality of pins parallel to the axis of the star-wheel and connecting the cam to the stud at the top and connecting the stud to the centre plate at the bottom, the pins being spaced outwardly from the centre of all said members. 90

3. In a braiding machine, a centre plate 95 having a circular groove which serves as a follower track and a loop track in the form of groove intersecting the main circular track, carriers having followers co-operating with said grooves, a top plate having corresponding tracks in the form of slots, carriers having followers to co-operate with the top plate slots, separate cam members forming the inner walls of the loop track in the top plate, star-wheels and an annular gear for actuating the carriers, means for rotating the centre plate and top plate, means for supporting and securing the cams comprising an upright stud for each cam forming a bearing for the star-wheel and a support for the cam, and means for securing the cams and the studs to the centre-plate comprising a plurality of pins parallel to the axis of the star-wheel and connecting the cam to the stud at the top and a plurality of pins also parallel to the axis connecting the stud to 100

105

110

115

130

the centre plate at the bottom, the pins being spaced outwardly from the centre of all said members, and a series of pins also parallel to the axis forming the points of intersection 5 of the circular grooves and the loop grooves in the centre-plate.

4. In a braiding machine, a centre-plate, a top plate, both said plates having circular tracks and loop tracks, the centre portions of 10 the loop tracks in the top plate being separate, means for supporting the centre portions inside the loop tracks in the top plate consisting of an upright member, means for securing the centre portions in position, comprising 15 prising a pin spaced out from the centre of the upright, securing the upright member to the centre plate and a pin likewise spaced out from the centre securing the central portion to the top of the upright member, said 20 pins being substantially parallel to the axes of the plates.

5. In a braiding machine a centre plate, a top plate, both said plates having circular tracks and loop tracks, the centre portions 25 enclosed by the loop tracks in the top plate being separate, means for supporting the centre portions of the loop tracks and top plate, consisting of an upright member, a pin spaced out from the centre of the 30 upright securing the upright member to the centre plate, a pin likewise spaced out from the centre securing the central portion to the top of the upright member, said pins being substantially parallel to the axes of the

plates, a series of pins seated in the centre 35 plate and forming the points of the walls at the intersections of the loop tracks in the circular track.

6. In a braiding machine, the combination 40 of a centre plate having a circular track in the form of a groove and intersecting loop tracks also in the form of grooves, a top plate having slotted tracks corresponding with those of the centre plate with a separate 45 centre member forming the enclosed portion within each loop track and star wheels for each loop track, a bearing member for the star wheels supported on the centre plate and supporting the centre portion of each 50 loop track, means for securing the said centre members in position, comprising pins parallel to the axis extending through the 55 centre portions into the bearing member of the corresponding star wheel, said pins being spaced out from the centre, pins similarly placed parallel to the axis and spaced out from the centre connecting the other end of the bearing member to the centre plate, pins seated in the centre plate at the points formed by the groove walls at the intersections of the loop tracks of the main tracks, and forming the operative surface of the 60 track at the point.

Signed by us at Baltimore, Maryland, this 11th day of May, 1925.

EDWARD C. DANDY.
WILLIAM TUGWELL.
